OPERATING DEVICE FOR AUTOMOBILE TRANSMISSIONS

William J. Bieber, Doylestown, and Rene L. Guerster, Maple Glen, Pa., assignors to Bieber Enterprises, Inc., Doylestown, Pa.

Filed June 30, 1969, Ser. No. 17,941

Term of patent 14 years

Int. Cl. D12—14

U.S. Cl. D14—6

FIG. 1 is a front elevational view of the operating device for automobile transmission;

FIG. 2 is a rear elevational view of the operating device for automobile transmission of FIG. 1;

FIG. 3 is a right side elevational view of the operating device for automobile transmission of FIG. 1;

FIG. 4 is a top plan view of the operating device for automobile transmission of FIG. 1;

FIG. 5 is a fragmentary sectional view of the underside as viewed from line 5-5, FIG. 1; and

FIG. 6 is an end view of the operating device for automobile transmission.

The lower part of the device is a flat planar upright member which has an appearance from the lefthand side in FIG. 1 substantially the same as the appearance shown in FIG. 3. The device is designed to extend upwardly through an opening in the floor of an automobile alongside a complementary device and the broken lines in FIGS. 1, 2, 3 and 4 show a typical environment in which the operating device for automobile transmission of the present invention is located.

We claim:

The ornamental design for operating device for automobile transmissions, as shown and described.
